Filed Dec. 16, 1957, Ser. No. 48,907

Term of patent 14 years

(Cl. D87—4)

The figure is a plan view of a hardboard sheet material or the like showing our new design.

The hardboard sheet material or the like is of conventional thickness.

A unit is enclosed within the dot and dash lines on the drawing, which unit is repeated in regular succession as indicated by the extension beyond the boundaries.

We claim:

The ornamental design for a hardboard sheet material or the like, substantially as shown and described.
